GOLF PUTTER

Marvin M. Chandler, 19471 Beach Blvd.,
Huntington Beach, Calif. 92646

Filed Feb. 27, 1967, Ser. No. 5,958

Term of patent 14 years

(Cl. D34—5)

FIGURE 1 is a first perspective view of my golf putter design;

FIGURE 2 is an end elevational view of the putter;

FIGURE 3 is a second perspective view of the device with the putting face of the club head shown in elevation;

FIGURE 4 is a third perspective view of the putter, showing the rear configuration of the club head in elevation;

FIGURE 5 is an enlarged side elevational view of the forward side of the club head;

FIGURE 6 is an enlarged side elevational view of the rear side of the club head;

FIGURE 7 is an enlarged end elevational view of the head;

FIGURE 8 is an enlarged top plan view of the putter head; and

FIGURE 9 is an enlarged bottom plan view of the putter head.

I claim:

The ornamental design for a golf putter, as shown.
